US0D1083615S

(12) **United States Design Patent** (10) **Patent No.:** **US D1,083,615 S**
(45) **Date of Patent:** **** Jul. 15, 2025**

(54) **BOTTLE**

(71) Applicant: **Kraft Foods Group Brands LLC**,
Chicago, IL (US)

(72) Inventors: **Pierre Leclerc**, Vaudreuil-Dorion (CA);
Matthew Robinson, Lake Saint Louis,
MO (US); **Laura Flanagan-Kent**,
Nicholson, GA (US); **Chi-Keung**
Edwin Li, Markham (CA); **Véronique**
Paradis, Québec (CA)

(73) Assignee: **Kraft Foods Group Brands LLC**,
Chicago, IL (US)

(**) Term: **15 Years**

(21) Appl. No.: **29/883,311**

(22) Filed: **Jan. 26, 2023**

(51) LOC (15) Cl. **07-01**

(52) U.S. Cl.

USPC **D9/563**; D9/550; D9/574

(58) **Field of Classification Search**

USPC D9/530, 542, 549, 550, 558, 563, 571,
D9/574, 575, 566

CPC B65D 2501/0081; B65D 1/0223; B65D
23/102

(57) **CLAIM**

The ornamental design for a bottle, as shown and described.

DESCRIPTION

FIG. 1 is a top front perspective view of a bottle according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dash-dash broken lines illustrate portions of the bottle and form no part of the claimed design. The dash-dot broken lines represent the bounds of the claim and form no part of the claimed design.

1 Claim, 5 Drawing Sheets
